[57] **CLAIM**

The ornamental design for a combined bridge and string anchoring device for bass guitars, as shown and described.

DESCRIPTION

FIG. 1 is a front, top and left side perspective view of a combined bridge and string anchoring device for bass guitars showing my new design.

FIG. 2 is a left side elevational view.

FIG. 3 is a front elevational view.

FIG. 4 is a rear elevational view.

The screw shaft threads are shown schematically for convenience of illustration in FIGS. 1-3.
